Primary Examiner — T. Chase Nelson*Assistant Examiner* — Kathleen M Sims(74) *Attorney, Agent, or Firm* — Morgan, Lewis & Bockius LLP(57) **CLAIM**

The ornamental design for a drum for washing machine, as shown and described.

DESCRIPTION

FIG. 1 is a perspective view of a drum for washing machine showing our new design;

FIG. 2 is a front view thereof;

FIG. 3 is a rear view thereof;

FIG. 4 is a left side view thereof where the right side view is a mirror image;

FIG. 5 is a top plan view thereof;

FIG. 6 is a bottom plan view thereof;

FIG. 7 is a reference perspective view thereof showing the state that the drum has been installed in the washing machine; and,

FIG. 8 is a reference perspective view thereof showing the state that the drum has been rolled up in order to be installed in the washing machine.

The broken lines are for illustrative purposes only and form no part of the claimed design.
